VIBRATING MASSAGE MACHINE

Lloyd A. Christensen, Lowell C. Christensen, William A. Christensen, and Weston W. Christensen, Lohrville, Iowa

Application February 25, 1957, Serial No. 44,975

Term of patent 14 years

(Cl. D83—1)

Fig. 1 is a front perspective view of a vibrating massage machine, showing our new design;

Fig. 2 is a side elevational view thereof;

Fig. 3 is a rear elevational view thereof; and

Fig. 4 is a top plan view thereof.

We claim:

The ornamental design for a vibrating massage machine, substantially as shown.
